SOLAR SYSTEM TEACHING UNIT

James T. Glisson, Evinston, Fla., assignor to Motivation
Systems, Inc., Gainesville, Fla.

Filed May 4, 1970, Ser. No. 22,806

Term of patent 14 years

Int. Cl. D19—07

U.S. Cl. D25—1

Fig. 2

Fig. 3

Fig. 2

FIG. 1 is a perspective view of the unit with the walls partly broken away to show the interior, the outer walls being plain and unornamented;

FIG. 2 is a side elevational view of the unit with the front side wall broken away, the outer walls being plain and unornamented;

FIG. 3 is a plan view of the unit with the top wall partly broken away, the outer walls being plain and unornamented;

FIG. 4 is an enlarged fragmentary view of one end of the interior of the unit; and

FIG. 5 is an enlarged fragmentary view of the other end of the interior of the unit.

The spheres illustrated in FIGS. 1 and 4 are suspended

by wires from the top wall of the interior of the unit. The spheres illustrated in FIG. 5 are attached directly to the side wall.

I claim:

The ornamental design for a solar system teaching unit, as shown and described.
